INVENTOR.

Arthur E. Templeman

BY George Bullock

ATTORNEY.

UNITED STATES PATENT OFFICE.

ARTHUR E. TEMPLEMAN, OF GRAND JUNCTION, COLORADO.

DESIGN FOR A BADGE, BUTTON, OR SIMILAR ARTICLE.

53,539.

Specification for Design.

Patented July 8, 1919.

Application filed May 14, 1918. Serial No. 234,540. Term of patent 3½ years.

To all whom it may concern:

Be it known that I, ARTHUR E. TEMPLEMAN, a citizen of the United States, residing at Grand Junction, in the county of Mesa and State of Colorado, have invented a new, original, and ornamental Design for a Badge, Button, or Similar Article, of which the following is a specification, reference being had to the accompanying drawing, forming part thereof.

The figure is a plan view of my design.

I claim:

The ornamental design for a badge, button, or other similar article, as shown.

ARTHUR E. TEMPLEMAN.
